UNITED STATES PATENT OFFICE.

WILLIAM H. GUILLEBAUD, OF HOBOKEN, NEW JERSEY.

PROCESS OF PRODUCING PHOTOGRAPHS IN RELIEF.

SPECIFICATION forming part of Letters Patent No. 242,414, dated May 31, 1881.

Application filed January 25, 1881. (No specimens.)

To all whom it may concern:

Be it known that I, WILLIAM H. GUILLEBAUD, a citizen of Switzerland, residing at Hoboken, in the county of Hudson and State 5 of New Jersey, have invented new and useful Improvements in the Production of Photographs in Relief, of which the following is a specification.

This invention has for its object an improvement 10 in embossed photographs, which can be produced in a rapid and comparatively cheap manner in bold rounded relief, instead of the flat relief so far obtained.

I am aware that as early as 1860 attempts 15 have been made to produce embossed photographs showing the principal figure in relief upon a suitable background; but as yet no embossed photo-portraits have been produced, as far as I know, for the simple reason that all 20 attempts have utterly failed to produce a better effect than that produced by the ordinary flat photographs, because all such embossed photo-portraits lack a bold rounded relief, with clean and correct edges, and with perfectly 25 accurate details, corresponding in every particular to the original.

My invention and process, as hereinafter described, is capable of many slight variations, and I will proceed to explain minutely that 30 method which I prefer, as follows:

The art of photography has attained such 35 perfection that anything but a perfectly accurate and artistically true relief imparted to them, instead of being an improvement, decidedly mars the beauty of the picture. The proper manufacture of a mold or die for embossing a photographic picture is an exceedingly delicate operation, although it can be done quickly and at a small cost, provided the 40 various minute details hereinafter explained are carefully observed.

First of all, for the purpose of taking the picture, a paper must be selected which is tough, not brittle, sized or not, and albumenized or 45 otherwise prepared. When the paper is being cut for printing it must be cut always in the same direction, for when being wet it stretches more in one direction than in the other, and if cut indiscriminately some of the points would 50 be too wide or too long, and they would no longer correspond accurately to the mold. After

the pictures have been transferred to the papers, or printed, I mount them on tough card-board; but great care must be taken in pasting, otherwise the pictures, if stretched in any 55 way, will not fit the mold. The prints may be mounted on card-board and then left to dry before embossing, or they may be placed on the mold unmounted and the card-board laid on with paste just at the time of exposing them 60 to the action of the embossing-die. Both ways give good results if done carefully.

I now take a negative (or positive, according to the further process which may be used) and retouch the same, so that all the dark parts 65 of the picture, which should be raised in the mold, be reproduced, as if they had been white instead of black, and all the light parts of the picture, which should be sunk in the mold, are retouched, so as to be black, or vice versa; (for 70 instance, dark hairs in the negative must be touched up so as to appear as they would if they had been white on the picture.) If the background is not wanted it is scraped off in the negative. Great care must be taken, however, to take the negative or positive larger 75 than the exact size of the picture to be embossed, as will be presently more fully explained.

The negative (or positive) is taken on ground 80 glass, either on the ground side or on the smooth side, if the glass is ground on one side only, but I prefer glass ground on both sides. A gelatine mold made by actinic action from a picture on plain transparent glass has sharp 85 rectangular edges throughout, so that in embossing the high white edges cut through the paper or other material to be embossed, and for this reason such molds cannot be used successfully for embossing. By using ground or translucent glass the light is diffused, and the edges of the gelatine mold become slanting; but in order to obtain rounded edges it is necessary to place the face of the picture at a slight distance from the sensitized medium—such as gelatine 90 or albumen, which is to make the mold—during exposure. The space between the picture and the gelatine, together with the diffusing effect of the ground glass, allows the diffused light to penetrate, so to say, under the edges of the 95 figure, and a mold is obtained with beautifully slanting and rounded edges and details, and

when this mold is used for embossing a picture is obtained without cuts, cracks, or tears, and more pleasing to the eye than if it had sharp abrupt edges, if such could be produced 5 without tearing the paper.

After the negative (or positive) on the ground glass has been varnished, as usual, by flowing a very thin white varnish on its face, I interpose between its face and the sensitized gelatine a coat of shellac or copal varnish, of greater or less thickness, or a pane or sheet of glass, mica, collodion, insoluble gelatine, or any other suitable material of the required thickness. Then I take the exposure by any of the known 10 processes, and a mold is obtained by actinic action on the film of sensitized gelatine, which may be of greater or less thickness, as required. From this mold I take, in the manner usually practiced, a plaster cast, which represents 15 the figure sunk. From this plaster cast I take, by known means, a cast in beeswax, gutta-percha, vegetable wax, pitch, or other equivalent material, which (when the figure in the plaster cast is sunk) shows the figure in relief. 20 This wax cast should not be more than about one-eighth of an inch in thickness. 25

Now, by comparing the size of the figure on the wax cast with that on the plaster cast it will be found that the former is considerably 30 smaller than the latter, owing to the shrinkage of the warm wax in cooling and solidifying. This shrinkage amounts to a trifle less than an eighth of an inch for each five inches, but it is somewhat different for different kinds 35 of wax or different materials, and it is also affected by different temperatures, rapidity of cooling, &c. No exact rule can therefore be laid down for all cases, and the shrinkage in different cases must be determined by actual 40 experiments.

As previously stated, the negative (or positive) must be taken larger than the actual size of the picture to be embossed, and in order to determine the exact proportion I take a wax cast 45 on a slab of plaster-of-paris having a graduated line or scale of, say, one foot in length. When cool I take off the wax cast, which shows the graduated scale. This wax scale, however, is shorter than that on the plaster-of-paris, due 50 to the contraction of the wax in cooling, and it serves to determine the size of the negative (or positive); for instance, if the figure or picture to be embossed measures five inches on the wax scale, the negative (or positive) taken therefrom 55 and serving for making the mold must measure five actual inches, or five inches on the plaster-of-paris scale.

The plaster cast from which the wax cast is obtained, as heretofore stated, being equal in 60 size to the negative or positive from which the mold is made, is of no further use; but the wax cast will show the figure in relief and of the exact size required for embossing the print, all the details being in proper relief, not according 65 to lights and shades or colors, but according to natural position and shape, only the

whole figure is flat, the natural roundness of the figure and details being lacking.

I now take an outline of the figure on tracing-paper from the photograph print to be embossed and paste this on a wooden tablet about three-sixteenths of an inch thick, and with a fine saw I follow the contour of the figure, producing a frame with an opening the edges of which correspond to said contour. This wooden frame 70 I heat on a hot iron or otherwise; then I place the wax cast on it, so that the edges of the opening come directly under the corresponding edges of the figure in the wax cast, (this is easily done by a simple pin-hole register or 75 any other suitable device,) then that portion of the wax cast which projects beyond the figure is gently pressed down upon the hot wood of the frame, to which it adheres strongly, so that the wax cast can be separated from said frame 80 only by being scraped or melted off. By these means the wax is backed with wood, leaving, however, the back of the whole figure free, and it is then fastened upon a small table with an opening at least as large as the opening in 85 the wood frame, thus leaving the figure, which is in relief, in the wax cast fully exposed to view. The operator or artist, having both 90 hands free, pushes up from under the wax cast to round up the whole form and he models the 95 figure, which, by a very few touches, assumes all the roundness and shape of the natural figure, so that all the details furnished by the primitive wax cast appear on a rounded form, while the edges of said cast remain slanting, 100 rounded, and perfect, as produced by the actinic action of the diffused light on the sensitized gelatine. The wax cast is bent and modeled by pressure both ways, up and down, if necessary, and a skillful operator can produce 105 a truly artistic mold in a very short time.

In order to prevent the wax mold from being flattened by subsequent handling I fill in the hollow space in its back by running plaster-of-paris in it, which is mixed with water to the 110 consistency of thick cream, and which, after having been run in, is scraped flush with the wooden back and left to harden. The face of the wax mold is then black-leaded and exposed to an electrotyping process, so as to obtain a 115 concave electrotype, which is carefully backed on its convex side with metal, and from which a counter-die can be taken in any suitable metal or material by known means. The prints, prepared as heretofore described, are then 120 placed between the concave electrotype and the counter-die, and by applying pressure they are embossed.

Great care must be taken to obtain the electrotype and the counter-die of even thickness, 125 and to place the prints on the electrotype so that they register properly, which is done by any of the numerous known ways of registering, so that the figure of the print meets the corresponding parts in the mold.

I do not here claim the process of making curved or rounded molds, dies, or matrices,

which consists in first obtaining a mold by the actinic action of light upon a sensitized medium through a photo negative or positive or other transparent or translucent picture, then 5 obtaining a plastic cast from such mold, applying this plastic cast to a border, frame, or backing, and then modeling the same in the desired manner, as this forms the subject-matter of a separate application for Letters Patent filed of to even date herewith.

What I claim as new, and desire to secure by Letters Patent, is—

The within-described process of producing a photographic picture showing the principal 15 figure in rounded relief, which consists in first obtaining, through the actinic action of light, a mold of sensitized gelatine or analogous sub-

stance with rounded and slanting edges, then producing from this mold a plaster cast, and from this plaster cast a cast of wax or other 20 plastic material, then modeling this plastic cast to correspond to the natural object, then producing from this modeled wax cast a concave electrotype and a counter-die, and finally 25 embossing the photographic print by the combined action of such electrotype and die, as set forth.

In testimony whereof I have hereunto set my hand and seal in the presence of two subscribing witnesses.

W. H. GUILLEBAUD. [L. S.]
